DESIGN FOR A LAMP OR SIMILAR ARTICLE

Albert H. Murray, Buffalo, N. Y.

Application December 5, 1939, Serial No. 38,685

Term of patent 3½ years

To all whom it may concern:

Be it known that I, Albert H. Murray, a citizen of the United States, residing at Buffalo, in the county of Erie and State of New York, have invented a new, original, and ornamental Design for a Lamp or Similar Article, of which the following is a specification, reference being had to the accompanying drawing, forming part thereof.

I claim:

The ornamental design for a lamp or similar article, substantially as shown.

ALBERT H. MURRAY.
